US00D945138S

(12) United States Design Patent (10) Patent No.: US D945,138 S
Mitchell et al. (45) Date of Patent: * Mar. 8, 2022

(54) SHOE

(71) Applicant: adidas AG, Herzogenaurach (DE)

(72) Inventors: Jared Mitchell, Carlsbad, CA (US);
Kelly Kikuta, Long Beach, CA (US)

(73) Assignee: adidas AG, Herzogenaurach (DE)

() Term: 15 Years

(21) Appl. No.: 29/769,497

(22) Filed: Feb. 5, 2021

Related U.S. Application Data

(63) Continuation of application No. 29/701,236, filed on Aug. 9, 2019, now Pat. No. Des. 909,727.

(57)

CLAIM

The ornamental design for a shoe, as shown and described.

DESCRIPTION

FIG. 1 is a bottom perspective view of a shoe showing the claimed design;

FIG. 2 is a bottom view thereof;

FIG. 3 is a top view thereof;

FIG. 4 is a right side view thereof;

FIG. 5 is a left side view thereof;

FIG. 6 is a front view thereof; and,

FIG. 7 is a rear view thereof.

The broken lines in the figures show portions of the shoe that form no part of the claimed design.

1 Claim, 7 Drawing Sheets
